UNITED STATES PATENT OFFICE.

MICHAEL SAGE, OF MCLEAN, ILLINOIS.

HOG-TRAP.

SPECIFICATION forming part of Letters Patent No. 730,049, dated June 2, 1903.

Application filed October 27, 1902. Serial No. 128,895. (No model.)

To all whom it may concern:

Be it known that I, MICHAEL SAGE, a citizen of the United States, and a resident of McLean, in the county of McLean and State of Illinois, have invented new and useful Improvements in Hog-Traps, of which the following is a full, clear, and exact description.

This invention relates to improvements in traps for receiving and holding hogs for nose-
ringing or other purposes, the object being to provide a portable hog-trap of simple construction that will operate quickly and that may be adjusted to hogs of any size.

I will describe a hog-trap embodying my invention and then point out the novel features in the appended claims.

Reference is to be had to the accompanying drawings, forming a part of this specification, in which similar characters of reference indicate corresponding parts in both figures.

Figure 1 is a perspective view of a hog-trap embodying my invention, and Fig. 2 is a front elevation thereof.

Referring to the drawings, 1 designates a creel having a door 2 at its rear end and mounted on runners 3, so that it may be easily transported from place to place. Arranged at the front of the creel are the neck-clamping jaws 4 5. These clamping-jaws are bifurcated at their upper ends, and in these upper portions are arranged rollers 6 7, movable on a track 8, attached to the front posts of the creel.

At one side of the creel and, as here shown, attached to the track 8 is a segment-rack 9, and pivoted to the end of the track is a lever 10, having a pawl 11 for engaging with the rack. This lever extends above and below the track, and the lower end is connected, by means of a link 12, with the upper end of the jaw 4, while the upper portion of said lever is connected, by means of a link 13, with the upper portion of the jaw 5. The lower ends of the jaws are movable between guide-strips 14 15. These guide-strips are extended outward from one side of the creel, and to these extended portions an angle-lever 16 is pivoted. On the outer end of the horizontally-disposed portion of this angle-lever is a foot-plate 17, and from the upper end of the vertically-disposed portion a link 18 extends to pivotal connection with the lower end of the jaw 4. From the horizontally-disposed por-

tion of this angle-lever 16 a rod 19 extends to a connection with another angle-lever 20, pivoted to a front post of the creel above the first-named angle-lever. From the downwardly-disposed portion of this lever 20 a pin 21 extends into a slot formed in the lower portion of the jaw 5, and a spring connection 22 is arranged between the creel and the horizontally-disposed portion of the lever. This spring serves to hold the lower portions of the jaws yieldingly separated. The lever carries a pawl 23 for engaging with a segment-rack 24. In operation by means of the lever 10 and its connections with the jaws the said jaws may be adjusted and so held for hogs of different sizes. The lower portion of the jaws will be separated yieldingly to permit the passage of the hog's head between the same. The hog upon being driven into the creel will naturally try to escape between the jaws. As soon as he shall have entered between the jaws pressure is to be applied to the lever 16, which will immediately close the jaws around the hog's neck, thus securely holding him.

While I have described the device as particularly adapted for holding hogs, it is obvious that it may be employed for holding calves or other small animals. The rollers at the upper end of the jaws permit of easy and quick adjustment.

Having thus described my invention, I claim as new and desire to secure by Letters Patent—

1. A hog-trap comprising a creel, a track at one end of the creel at the upper portion, clamping-jaws, rollers attached to said jaws and engaging on the track and means for drawing the jaws together at the lower portion.

2. A hog-trap comprising a creel, a track at one end thereof and near the top, clamping-jaws, rollers attached to said jaws and engaging on the track, a lever, a link connection between said lever below its pivotal point and one of the jaws, a link connection between said lever above its pivotal point and the other of said jaws, means for holding the lever as adjusted, and means for moving the lower portions of the jaws.

3. A hog-trap comprising a creel, jaws mounted to swing at one end of said creel, guide-strips between which the lower ends of

the jaws are movable, an angle-lever, a link connection between the vertically-disposed portion of said angle-lever and one of the jaws, another angle-lever having sliding connection with the other of said jaws, and a rod connection between the two angle-levers.

4. A hog - trap comprising a creel, jaws mounted to swing at one end of the creel, guide-strips between which the lower ends of the jaws extend, an angle-lever, a link connection between the vertically-disposed member of said lever and one of the jaws, another angle-lever pivoted to the creel, the downwardly-disposed member of said other angle-lever having connection with the other of

20
said jaws, a spring connection between the creel and the horizontally-disposed member of said other angle-lever, a segment-rack, a pawl carried by the said other angle-lever for engaging with said rack, and a rod connection between the horizontally-disposed members of the two angle-levers.

In testimony whereof I have signed my name to this specification in the presence of two subscribing witnesses.

MICHAEL SAGE.
